UNITED STATES PATENT OFFICE.

RICHARD H. GRIFFITH, OF BELLEVUE, OHIO, ASSIGNOR TO THE OHIO CULTIVATOR COMPANY, OF BELLEVUE, OHIO, A CORPORATION OF OHIO.

CULTIVATOR.

Application filed October 27, 1923. Serial No. 671,265.

To all whom it may concern:

Be it known that I, RICHARD H. GRIFFITH, a citizen of the United States, residing at Bellevue, in the county of Huron and State 5 of Ohio, have invented certain new and useful Improvements in Cultivators, of which the following is a specification, reference being had therein to the accompanying drawing.

10 This invention relates to improvements in cultivators for the cultivation of fields having therein crops of growing corn.

The first and foremost object of my invention is carried out by the combination of 15 mechanism comprising on the one part a draft frame, a wheeled axle, and shovel beams coupled to the draft frame and adapted for vertical adjustment, so that the shovels may be let down to the ground or 20 be lifted upward out of cultivating position, and, on the other part, a fore and aft slide- able or adjustable seat frame, and beam-operating levers connected through suitable 25 devices with the beams and with said seat frame, so that when the beams are raised and cast additional weight on the machine back of the axle, the seat frame will advance forwardly to correspondingly reduce the weight rearward of the axle, whereby the 30 machine is duly balanced on the axle, as well when the beams are up as when they are down with the shovels in the soil.

A subsidiary feature involved in so carrying out the first object is composed of the 35 draft frame fixed with relation to the axle, and of the seat frame mounted to travel back and forth on the main frame through a sliding connection, including rollers which travel with the seat frame and ride against 40 the main frame, as on a track; whereby friction due to adjusting the seat frame forward and backward is reduced, and the adjustment made easy and smooth, notwithstanding 45 that at such times the seat frame is carrying the driver or operator, whose weight is added to the inertia of the seat frame.

Another object of my invention has reference to slidably mounting a transverse shaft 50 on which the couplings of the shovel beams are mounted and to which shaft also are connected the steering arms which control the angling or deflecting of the wheel spin- dles and ground wheels for directing the course of the cultivator, such slidable mount-

ing of such shaft being effected by means 55 of rollers mounted on the main frame and supporting and carrying a transverse bar connected to such shaft, so that when the shaft is adjusted laterally to position the cultivator beams more or less to one side of 60 the machine or the other, this transverse bar will travel on these rollers and make easy and free such lateral adjustment of the beams and angling or deflecting of the 65 wheels; the beams shifting to the left when the wheels are deflected in that direction, and shifting to the right when the wheels are deflected in that direction.

Another object of my invention is that 70 of combining with the shovel beams, the fore and aft adjustable seat frame, and their connections, certain lifting springs which, when the beams are down in working position are put under tension, so that when the beams are to be lifted and the seat frame to 75 be advanced forwardly, the retractile force of these springs will aid the operator in the act of lifting the beams and advancing the seat frame.

Other objects relating to structural and 80 detail features will appear from the specification.

In the accompanying drawings, forming a part of this specification,—

Figure 1 is a perspective view of my im- 85 proved cultivator with one wheel removed to facilitate the illustration, showing my cultivator in the normal position, or with the cultivator beams and shovels in cultivating position.

Figure 2 is a like view showing the position of the parts when the beams have been 90 lifted and the seat frame rolled or adjusted to forward position, to balance the machine in respect to the distribution of its weight 95 forward and rearward of the axle.

Figure 3 is a perspective view of my cul- 100 tivator, looking downward upon the ma- chine, with the parts in the position shown in Figure 2.

Figure 4 is a detail view, on a larger scale, showing the bracket and other de- vices involved in adjusting the beams later- ally.

Figure 5 is a detail perspective view show- 105 ing more clearly the relation of the sta- tionary draft frame and adjustable seat frame with the rollers carried by the latter

and traveling on the former as also some of the adjacent parts and the forward devices for the attachment of the cultivator beams.

5 Figure 6 is a detail perspective view showing the same parts at another angle or view point to effect a fuller illustration.

1 indicates the usual draft pole with its single trees 2 and draft devices including 10 draft rods 3 and links 4 connected with the shovel beams, so as to apply the draft strains produced by the team directly to the shovel beams. This pole is secured to the draft frame comprised of diverging bars 5 and 15 parallel bars 6, the rear ends of which are connected as by a bracket 7 to the axle 8, which is composed of two sections each bent to form a horizontal and a vertical part to constitute an arch. On the vertical 20 portions of the arch are mounted sleeves 9, which carry the pintles 10 for the ground wheels 11 and the steering arms 12, both of which extend forward and upward where they connect with a suitable coupling 13, 25 which fits on the transverse shaft 14. Each coupling has an upper extension 15 which receives and is secured to the transverse bar 16, so that such shaft and such bar are connected together, and when adjusted move in 30 unison. The bar 16 is slideable on the side members 6, within brackets 17, secured to the side members 6 of the main frame.

Thus this shaft and bar constitute a laterally adjustable member by which the wheels 35 are angled or deflected for steering the machine in either direction laterally, while the shovel beams are likewise adjusted both at a time in either direction through their connection with this transverse shaft 14. The 40 connection of the shovel beams, designated 19, with this shaft, is effected through the couplings 20. These couplings are rotatably mounted on the shaft 14 so that they will slightly oscillate when the shovel beams 45 are raised and lowered in the manner presently to appear. These couplings are also slidably mounted on such shaft so that the distance between them may be varied when it is desired to adjust the beams closer together or further apart to adapt them to the 50 row of corn to be cultivated.

Two separate instrumentalities are used 55 for adjusting the transverse shaft 14 laterally, and for adjusting the beams to and from each other without adjusting the shaft 14. The former of these instrumentalities comprises two bellcrank levers 21, mounted on pivot bolts 21^a, carried by brackets 22 secured to the main draft frame 5—6, and 60 links 23 attached at one end to the outer members of the bellcrank levers, and at the other end to projections 24 secured in any convenient manner to the shaft 14. The inner ends of the bellcrank levers are connected to other links 25 which, through

chains 26, are attached to the upper ends of foot levers 27, pivoted at 28 to any suitable connection with the main frame or arch.

When the operator places his foot upon either of the foot levers 27 and pushes it forward, he will therefore, through the connections described, shift the transverse shaft 14 and its connected cross bar 16 laterally in either direction, according to which foot lever he manipulates. This causes the bar 70 to slide on the frame 6 and the shaft to carry the cultivator beams laterally through their connection with this bar by means of the bracket 20. At the same time, the wheels are angled or deflected by the movement 75 thus given to the steering arms 12. Thus the beams with their shovels are adjusted laterally, while the wheels are correspondingly angled or deflected, which results in a quick direction of the shovels and of the 80 whole machine as well to one side or the other to meet the sinuosities of the rows of growing plants, as well as to dodge such haphazard obstructions as stones, roots, or 85 small stumps, where such conditions obtain, as they do in some fields.

To adjust the beams with their shovels closer together or further apart, the other set of instrumentalities is used, comprising a bracket 29 secured to the transverse shaft 95 14, and bar 16, a hand lever 30 pivoted to said bracket and having a link 31 at one side of its center, which connects with one of the brackets 20, and a link 32 at the other side of its center, which connects with the other bracket 20, so that by manipulating this lever the two shovel beams are adjusted closer together or further apart. By snapping, say, the inner end 100 of the link 31 into any one of the holes 105 shown in the bracket 29, the parts are locked in any given position. A rod 25^a is secured to the rear cross bar of the draft frame and to the bracket 29, to act as a brace.

I will now refer to the seat frame, and the 110 manner of mounting it on the machine. This frame comprises side members 33, a transverse brace 34 between them, converging bars 35 and seat supports 36, on which is placed a seat 37. The bars 33 lie adjacent 115 to the side bars 6 of the fixed draft frame, and the rollers 38, journaled to the side bars 33, travel upon the bars 6, while other rollers 38, journaled in the lower ends of the bars 33, travel on the under edge of the 120 draft frame, all as clearly shown in Figure 1. A guide strap 40, mounted on the journals of the rollers, overlaps one side of the draft frame, while the downwardly curved portion 41 of the seat member overlaps the 125 other side of the same member. In this way, the seat frame is mounted to reciprocate on the draft frame, and prevent it from being dislocated.

Certain instrumentalities are used to ad- 130

just the seat frame forwardly when the shovel beams are raised and to adjust it rearwardly when these beams are lowered to place the shovels in the ground. In the latter position, much of the weight of the beams and their shovels is sustained by the ground, and is not sustained at all by the machine frame at points back of the arched axle. In that condition, the seat frame occupies its rearward position, so that its weight and that of the driver will substantially balance all that part of the weight of the machine which is forward of the axle. But when the shovel beams are raised, and much of their weight and of the shovels is then supported by a connection at the rear of the axle, the seat frame moves forward so as to reduce the leverage of the weight of the frame and the driver, to compensate for the weight added by the elevation of the beams.

Instrumentalities other than those now to be described may be employed for so adjusting the seat frame and the shovel beams but those illustrated, and now set forth, are preferred. These instrumentalities comprise links 42 connected one at either side to the seat frame through the bolts 38^a on which the rollers 38 are mounted, and to segments 43, mounted each on a rock shaft 44, having bearings in the brackets 45 carried by the axle.

These segments 43 are thrown forward to advance the seat frame, and thrown rearward to return the seat frame. The segments are so moved by means of a lever 46, pivoted at 48 on a bolt carried by the adjacent member of the seat frame. This lever extends below its pivot to the point 49, where, through a link 50, it connects with an arm 51 secured to the rock shaft 44. Thus the segments 43 are oscillated back and forth, and through the links 42 the seat frame is adjusted. At the same time the shovel beams are raised or lowered, as the case may be, through levers 52, pivoted at 53, to the segments 43, with which they may be locked by the detent 54, shown more clearly in Figure 3, so that when the segments 43 are manipulated by the lever 46 as described, the levers 52 are swung to cause their rear ends 55 to lift or lower the shovel beams through the rods 56. Collars 57 on these rods serve to permit the adjustment of the tension of the pressure springs 58, so as to hold down yieldingly upon the shovels when they are working in the ground.

The lever 46 through its detent 46^a may be locked to the segment 46^b to hold the seat frame forward or backward, and the levers 52 and rods 56 in either position, so as to control the position of the shovel beams. And the levers 52 may be engaged or disengaged through their detents 54 with the seg-

ments 43, to adjust and hold either beam without adjusting the other, or indeed both at the same time, should that be desired, without operating the lever 46.

While this is not a feature of my invention, I call attention to the fact that the lever 59 is used to vary the inclination of the pole 1 with respect to the draft frame, so that the pole may be inclined upwardly or downwardly, or presented in alignment with such frame as may be desired in raising or lowering the forward ends of the shovel beams so as to affect the inclination of the shovels to the soil. This lever 59 has a detent 60 by which it may be locked to a segment 61 mounted on the pole, while a link 62 connects the lever with the forward part of the draft frame.

It will now be understood that besides the detail features of arrangement and construction, my invention comprises the two general features of the seat frame adjustable forwardly and rearwardly in connection with means for lifting and lowering the shovel beams in substantial unison with these movements, respectively, of the seat frame, and that in respect to these features there are the additional ones of detail and arrangement above described, which enter into these adjustments and mountings of the seat frame and beams.

Further it will be noted that my invention comprises also the transversely adjustable shaft and bar mounted on rollers and connected up with the wheel spindles by steering arms, with devices to so adjust the shaft and bar, and thereby the shovel beams connected with the bar, that when the beams are shifted laterally, the wheels are correspondingly deflected.

In order to lessen the labor or effort of the driver in lifting the shovel beams and advancing the seat forward, I have combined with the beams and the arch or other fixed place on the machine, a retractile or lifting spring 62^a, one for each beam. These springs are preferably of the coiled form, and are fastened at their lower ends to the beams as seen at 63, and at their upper ends to a fixed point on the frame, say to the arch itself, as indicated at 64, which is best shown in Figure 5.

It will be seen that when the shovel beams are in working position as illustrated in Figure 1, these lifting springs are distended or under tension. When the lever 46 is thrown forward to lift the beams and advance the seat forwardly, these springs join in the operation, and by their retractile force pull or lift on the beams, and so exert a force which is applied also to the seat frame through the several connections. In this way these lifting springs co-act with the beams, the seat frame, and the operating parts.

I may add that I prefer to provide a link 24^a, secured to the draft frame 5, and adapted at its other end to engage the forward part of the bracket 29, to lock the shaft 14 and bar 16 against lateral movement, so as to hold the wheels and spindles in a fixed position to make a rigid-axle cultivator of the machine when desired.

Having thus fully described my invention, 10 what I claim as new, and desire to secure by Letters Patent, is:

1. In a cultivator, the combination with a general frame including a draft frame having a fixed relation to the axle, of a seat 15 frame whose forward portion is slidably mounted on the draft frame, and rollers interposed between the two frames to facilitate adjustment to the traveling of the seat frame backward and forward.

20 2. In a cultivator, the combination with a draft frame, of a seat frame adapted to be adjusted forwardly and rearwardly, rollers mounted on the seat frame and arranged to travel on the other frame, and lever devices 25 by which to adjust the seat frame.

3. In a cultivator, the combination of a draft frame, a seat frame whose rear end carries a seat and whose forward portion is mounted to travel back and forth on the 30 draft frame, the forward end extending below such frame and carrying rollers which travel on the under side of the draft frame, and other rollers mounted on the seat frame and traveling on the upper surface of the 35 draft frame.

4. In a cultivator, the combination with a draft frame, of shovel beams connected thereto at their forward ends, lifting devices connected to their rear portions, a seat 40 frame slidably mounted on the draft frame, an actuating lever for the shovel beams and seat frame, and devices connecting such lever with the seat frame and the lifting devices.

45 5. In a cultivator, the combination with an axle and a draft frame fixed with relation thereto of a seat frame slidably mounted on the draft frame, a lever connected with the seat frame to adjust it forwardly and rearwardly, shovel beams with their forward 50 ends connected to the draft frame, lifting

devices connected to their rear portions, and with said lever, whereby when the shovel beams are raised the seat frame is advanced forwardly to compensate for the increased downward pull on the main frame due to 55 the suspension of said beams.

6. in a cultivator, the combination with an axle and a draft frame fixed with relation thereto, of a seat frame having rollers connected with its forward portion and adapted 60 to travel on the draft frame, shovel beams connected to the draft frame at their forward end, lifting devices connected to their rear portions, and a lever connected with said devices and with the seat frame, and 65 adapted to move the seat frame forward when the beams are lifted and rearward when the beams are lowered.

7. In a cultivator, the combination with an axle and a frame connected thereto, of a seat 70 frame adjustably mounted for fore and aft movement with respect to said other frame, shovel beams having their forward ends connected with the latter frame, lifting devices attached to their rear portions, a lever connected with such devices and with the seat frame, lifting springs connected with the beams and with a fixed part of the machine, and adapted to co-act with said lever in lifting the beams and advancing the seat 75 frame forwardly.

8. In a cultivator, the combination with an axle and a frame connected thereto, of a seat frame having its forward end mounted on said other frame and adapted to travel fore 80 and aft, with respect to said other frame, a lever connected with the seat frame to so adjust it, shovel beams connected to the machine frame at their forward end, lifting devices attached at their rear portions and connected with said lever, and retractile springs attached to the beams and to a fixed point on the machine, and adapted, when the shovels are in the ground, to give the beams a sort of floating action, and, when the 85 beams are lifted, to co-act in raising them and advancing the seat forward.

In testimony whereof, I affix my signature.

RICHARD H. GRIFFITH.
